STOVE OR RANGE

Henry A. Ahrens, Cleveland, and Emmett F. Kennedy, Garfield Heights, Ohio, and Joseph E. Nason, Erie, Pa., assignors to The Cleveland Co-Operative Stove Company, Cleveland, Ohio, a corporation of Ohio

Application October 30, 1931, Serial No. 571,956

8 Claims. (Cl. 126—42)

The present invention relating as indicated to stoves or ranges has more particular reference to novel and attractive structural features for a "console" type of cooking stove or cabinet, in which the burner section is placed substantially in the same plane as the top of the oven.

The general object and nature of our invention is to provide a unique and attractive construction of reciprocally movable cover plates which, when in closed position, have the effect of completely enclosing the operating parts of the stove, with the result that the stove or range, when not in use, will assume the pleasing appearance of an article of furniture such as a cabinet or the like. Another object of this invention is to be found in the provision of means for correlating the opening and closing movements of the top cover plate and the front valve handle closure plate.

Another object is to provide means under the sliding top cover whereby in its completely closed position it shall be raised to a position flush with the contiguous oven top cover; and in its completely closed position, it will be conveniently positioned underneath the oven top.

Another object is to provide means whereby the cover plate or the valve handle enclosing plate cannot be moved to closed position unless all of the burners are completely turned off, thereby calling the operator's attention to open valves and likewise preventing the accidental smothering of a burner flame with the coincident escape of unburned gas.

Advantages and objects additional to those discussed above shall become manifest during the following description. To the accomplishment of the foregoing and related ends, said invention then, consists of the means hereinafter fully described and particularly pointed out in the claims.

The annexed drawings and the following description set forth in detail certain structure embodying the invention, such disclosed means constituting, however, but one of various structural forms in which the principle of the invention may be used:

In said annexed drawings:

Fig. 1 is a perspective view, with portions cut away, illustrating the cover plates and mechanism constructed according to the principle of our invention; Fig. 2 is a plan view partially in section of the valve handle closure plate; Fig. 3 is an elevational view of Fig. 2; Fig. 4 is an elevational view taken upon a plane normal to that of Fig. 3 and illustrating an alternative form of construction for the valve handle closure plate actuating mechanism. Fig. 5 is a perspective

illustrating the improvement embodying our invention as assembled in a stove or range, and with the burner section cover plate in closed position; Fig. 6 is a view similar to Fig. 5, but with the burner section cover plate in opened position; Fig. 7 is a fragmentary longitudinal sectional view taken through Fig. 5.

Referring more particularly to Fig. 1, and Figs. 5 to 7 inclusive, there is shown the top of the oven section of a stove or range, which is indicated generally by the numeral 1. The open burner section, generally referred to by the numeral 1', is positioned to the left and substantially in the same plane as that of the top of the oven section. A trackway consisting of the horizontal channels 2 and 3 is positioned across the top of the stove and serves as a means for slidably supporting the burner section cover 4. The cover 4 has a pair of reversely bent lateral flanges 5 and 6 which are adapted to ride upon the tracks 2 and 3. A suitable handle 7 may be provided on the left hand edge of the cover 4 in order to facilitate its manipulation.

When the burner section cover 4 is open it will assume a position indicated by the dotted lines in Fig. 1, and as shown in Fig. 6. A second oven top cover 40 is placed above the oven top 1 and provides a space for the reception of the horizontal movable cover 4 when in open position.

When the cover 4 is moved to completely closed position, the beveled lugs 8 and 9 will bear against the flange 10 resulting in an elevation of the cover 4. Similar vertically extending lugs or fingers 11 and 12 positioned upon the ends of the trackways 2 and 3 respectively, likewise serve to impart a final raising or elevating movement to the burner cover 4. It will thus be seen that the above described mechanism permits the burner cover 4 to drop to a plane lower than the oven top cover and to be slid out of view under the oven top cover when in open position, and to be raised to a plane flush with the oven top cover when in closed position, as best shown in Figs. 5 and 7.

Now directing attention to Figs. 2 and 3, for the purpose of enclosing the valve operating handles 13, there has been provided the horizontal movable closure plate or panel 14. The closure plate 14 is supported in its horizontal movement by means of a pair of horizontal arms 15 and 16 secured to the inner face of the plate 14. The inner ends of the arms 15 and 16 are slidably positioned in the sleeves 17 and 18 respectively, which are in turn secured to the frame of the stove. The plate 14 has in its face, a

plurality of openings 18 which are adapted to register with the valve handles 13 when the latter are in closed position.

In order to actuate the closure plate 14 in its reciprocal horizontal movement, there is provided the lever bar 20 which is pivotally secured at the points 21 and 22 to the bosses 23 and 24 respectively which are in turn mounted upon the stove frame. The offset portion 25 of the lever bar 20 engages with slots at the end of the inwardly extending lugs 26 and 27 secured to the inner face of the cover 14.

Returning to Fig. 1, the upper end 28 of the lever bar 20 is engaged by an opening in the end of the rocker arm 29. The rocker arm 29 is pivoted at the point 30 and has one end slightly curved as shown at 31. A vertical flange 32 on the rocker arm 29 is adapted to be engaged by a slot 33 in the flange 16 of the burner cover 4. A tension spring 28 attached to the end of the rocker arm 29 tends to hold the moving parts against vibration and to insure positive movement of the actuating levers.

It will thus be seen that by means of the last described mechanism the valve handle closure plate 14 will be automatically opened and closed upon opening and closing movement of the burner cover 4. It should be further noted that when the cover 4 and the handle cover 14 are in open position, and any one of the valve handles 13 are not in closed position, as represented by the dotted lines in Fig. 4, they will not register with the openings 18, therefore rendering impossible the closing of the respective covers.

When it is found desirable to operate the valve handle closure plate 14 independently of the burner cover 4, there may be provided the actuating mechanism illustrated in Fig. 4. In this latter alternative form of construction the lever bar 20 is extended above the top plane of the burner grate 34 with an operating handle 35 on its end. It will thus be seen that movement of the operating handle 35 will move the valve handle closure plate 14 to the position shown by the dotted lines in Fig. 4. It will thus be seen from the foregoing description that we have provided a mechanism which not only adds to the pleasing and attractive appearance of a stove or range assembly, but also possesses unique precautionary features.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a stove or range, the combination of a burner section, an oven adjacent said burner section, a raised top on said oven, and a cover for said burner section adapted to horizontally slide under said raised top, and means for elevating said cover to a plane coincident with said top when said cover approaches closed position.

2. In a stove or range, the combination of a burner section, an oven adjacent said burner section, a raised top on said oven, a cover for said burner section adapted to horizontally slide under said raised top, a track for slidably supporting said cover, and vertical projections adapted to contact with the under side of said cover for elevating it to a plane coincident with said top when approaching closed position.

3. In a stove or range, the combination of a plurality of valve handles, a panel member disposed at all times in a vertical plane and having a plurality of non-circular openings for the registry of said valve handles, said handles being of a non-circular contour whereby they are locked against rotation when aligned with said panel member and horizontally disposed means for movably supporting said panel member, said supporting means being adapted to permit the forward movement of said panel member to a position in alignment with said valve handles and permitting the movement of said panel member to a position in the rear of said valve handles.

4. In a stove or range, the combination of a plurality of valve handles having a non-circular contour, a panel member disposed at all times in a vertical plane and having openings therein of a form similar to the contour of said valve handles and for the registry of the latter, and horizontally disposed means rigidly attached to said panel member for slidably supporting the latter whereby said panel member is adapted to be moved from a position in alignment with said valve handles to lock them against turning in said openings, and thence to a position in the rear of said valve handles to unlock them.

5. In a stove or range, the combination of a plurality of valve handles, a vertically disposed panel member having non-circular openings adapted to register with said valve handles, said handles being of a non-circular contour whereby they are locked against rotation when aligned with said panel member horizontally projecting members rigidly secured to the inner face of said panel member and slidably mounted on said stove, and means for permitting the forward movement of said horizontal members to a position where said panel member is in alignment with said valve handles, and permitting rearward movement of said panel member to a position past said valve handles.

6. In a stove or range, the combination of a burner section, a cover for said section adapted to be horizontally movable thereover, operating valve handles for said burner section, a horizontally movable panel member having openings adapted to receive said valve handles only in the closed position of the latter, supporting means on said stove for movably carrying said panel member into and out of the common plane of said handles, and lever mechanism connected with said cover for automatically moving said handle enclosing panel member on movement of said cover.

7. In a stove or range, the combination of a burner section, a cover for said section adapted to be horizontally movable thereover, operating valve handles for said burner section, a horizontally movable panel member, supporting means on said stove for movably carrying said panel member into and out of the common plane of said handles, lever mechanism connected with said cover for automatically moving said handle locking panel member on movement of said cover, and openings in said panel member for the reception of said handles only when the latter are in closed position and adapted to permit the closing of said cover and said panel member only when said handles are in closed position.

8. In a stove or range, the combination of a burner section, an oven adjacent said burner section, a raised top on said oven, a cover for said burner section adapted to horizontally slide under said raised top, means for elevating said cover, and vertical projections adapted to contact with the under side of said cover for elevating it to a plane coincident with said top when approaching closed position.

5 cover to a plane coincident with said top when said cover approaches closed position, operating valve handles for said burner section, a horizontally movable panel member, supporting means on said stove for movably carrying said panel member into and out of the common plane of said handles, lever mechanism connected with said cover for automatically moving said handle locking panel member on movement of said cover,

and openings in said panel member for the reception of said handles only when the latter are in closed position and adapted to permit the closing of said cover and said panel member only when said handles are in closed position. 5
